(57) **CLAIM**

The ornamental design is for a rugged laptop computer, as shown and described.

DESCRIPTION

FIG. 1 is a top, front and right side perspective view showing my new design;

FIG. 2 is a top, rear and left side perspective view thereof; FIG. 3 is a bottom, rear and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is another top view of the rugged laptop computer of FIGS. 1-9 shown in an alternate position where the screen is closed and the handle of the design is pulled out.

The broken lines showing portions of the rugged laptop computer are included for the purposes of illustrating portions of the article and form no part of the claimed design.

1 Claim, 10 Drawing Sheets
